CLAIM

The ornamental design for a beaded beverage holder, as shown and described.

DESCRIPTION

FIG. 1 is a side elevation view of a beaded beverage holder showing my new design, the opposite side elevation view being identical and symmetrical;

FIG. 2 is an enlarged front elevation view thereof, the rear elevation view is identical and symmetrical;

FIG. 3 is a top plan view thereof;

FIG. 4 is a bottom plan view thereof; and,

FIG. 5 is an enlarged vertical cross-sectional view taken along line 5—5 of FIG. 2.

The strap is shown broken away in FIGS. 2, 3 and 5 for convenience of illustration.
